A. A. ARNOLD

LENS HOLDER

Filed Oct. 26, 1916

INVENTOR
ARTHUR A. ARNOLD

BY

H. H. Styll & H. Parsons
ATTORNEYS

UNITED STATES PATENT OFFICE.

ARTHUR A. ARNOLD, OF SOUTHBRIIDGE, MASSACHUSETTS, ASSIGNOR TO AMERICAN OPTICAL COMPANY, OF SOUTHBRIIDGE, MASSACHUSETTS, A VOLUNTARY ASSOCIATION OF MASSACHUSETTS.

LENS HOLDER.

Application filed October 26, 1916. Serial No. 127,811.

To all whom it may concern:

Be it known that I, ARTHUR A. ARNOLD, a citizen of the United States, residing at Southbridge, in the county of Worcester 5 and State of Massachusetts, have invented certain new and useful Improvements in Lens Holders, of which the following is a specification.

My invention relates to improvements in 10 cutters and has particular reference to an improved construction of machine for readily cutting or forming a slot in the edge of an ophthalmic lens or the like.

One of the leading objects of my invention 15 is the provision of a novel and improved attachment which may be readily applied to a lens drill or similar machine and will enable said machine to be used in edge slotting of lenses.

20 A further object of the invention resides in the provision of certain novel and improved details of construction particularly adapted for use in connection with my present device, although capable of use in other 25 forms of lens slotters if desired.

Other objects and advantages of my improved construction should be readily apparent by reference to the following specification taken in connection with the accom- 30

panying drawings, and it will be understood that I may make any modifications in the specific details of construction shown and described within the scope of the appended claims without departing from or 35 exceeding the spirit of my invention.

Figure I is a perspective view of my attachment applied to a well known form of lens drill.

Figure II is a perspective view of the 40 face of my attachment with a lens in position therein.

Figure III is a view of a slightly modified construction.

Figure IV is a sectional view as on the 45 line IV—IV of Figure III.

In the drawings, the numeral 1 designates the drill base from which rises a standard 2, on which is pivotally mounted the usual lens clamping mechanism 3, including the 50 pair of jaws 4 and 5 each provided with block pins 6. Rising from the base 1 near the jaws 4 and 5 is the drill standard 7

having slidably and rotatably mounted therein the spindle 8 driven as through the pulley 9 and adapted to be reciprocated by movement of the handle 10, a suitable stop screw 11 being provided to limit the downward movement of the handle, while suitable means, such as a spring, not shown, may be employed if desired to shift the 60 spindle 8 into raised position.

This improved attachment can be readily applied to any well known form of lens drill or similar machine, but for the purpose of clearly illustrating the application 65 of the same to a lens drill it is shown in connection with a machine similar to that illustrated in the patent issued to George H. Day, No. 807,064, patented December 12, 1905. 70

Ordinarily the spindle 8 has secured at the lower end thereof as by the clamp collar 12 a suitable drilling point, but when used for my improved purposes I have shown as substituted for this drilling point 75 the spindle 13 bearing the slotting wheel 14. It will thus be seen that the wheel 14 may be readily substituted for the drilling point as desired, and the horizontal position of the wheel 14 controlled by shifting of 80 the handle 10.

To retain the lens in proper position to engage this wheel I may employ my improved device, comprising the base block 15 having at each side the pair of sockets 85 16 adapted to receive the pins 6 to insure exact positioning and firm non-rocking retention of the base block between the jaws 4 and 5, while rising from the base block, as illustrated in Figures I and II, is the 90 bracket 17 bearing the pair of lens engaging pins 18. In addition, the bracket 17 has extending forwardly therefrom the guide rod 19, on which is slidably mounted the lug 20 and handle portion 21 formed 95 on the plate 22, a spring 23 interposed between the lug 20 and the block 24 secured on the guide rod 19 serving to force the plate 22 inward toward the pins 18. A second pair of pins 25 carried by the 100 plate thus serves to securely clamp a lens in exact centered position between the pairs of pins, attention being called to the fact that the pins are shown as centrally re-

duced, or of hour glass formation to securely engage the edge of the lens and prevent accidental lateral movement of the lens relative to my clamping device.

- 5 In the use of the form of construction just described it is merely necessary to clamp my device in position between the jaws 4 and 5, and to then outwardly shift the plate 22 by grasping of its handle 21
10 and insert the lens between the pins 18 and 25; the lens having been placed in position the regular lens clamping mechanism 3 is swung about its pivotal support, namely the standard 2, to move the entire device,
15 including the lens, against the cutting or slotting wheel 14 to cause the slotting of a lens.

It will be understood that it is preferable to keep the wheel 14 moistened during
20 the slotting operation, and to best accomplish this result I may if desired secure to the standard 7 the sponge cup 26 having a sponge, which will bear against the outer face and edge of the cutter 14 while the lens
25 is in engagement therewith and keep it moistened. To control the moistening of the sponge I may place either on the standard 7 or on the bracket 17, a tank 27 having a discharge spout 28 adapted to convey moisture to the sponge cup, the flow from the tank to the sponge cup being controlled as by the plunger valve 29 so disposed as to be engaged in the form shown by the bracket 17, or, if the tank is on the bracket 17, then
30 to be engaged by the standard 7 as the bracket is swung inward, whereby the valve is automatically opened and feeds liquid to the sponge cup while the parts are in operation and the flow of liquid is automatically shut off as soon as the parts are shifted
40 out of operative position.

In connection with the form just described when it is desired to slot the lens at other than its exact center the position normally
45 occupied by the wheel 14, slotting below center may be accomplished by suitably adjusting the stop screw 11 and holding the handle down thereagainst with the one hand while the device is swung with the other hand, this permitting of slotting at any
50 desired point along the edge of the lens within the range of movement of the cutter 14.

In Figure III, I have illustrated a slightly modified form of my invention, which
55 may be used either with the form of drill illustrated or with other types of drills in which the lens holder is normally stationary, and in which the feed is controlled by my
60 device. In this form of invention I slidably mount the plate 22' on the bracket 17' as previously described, but in place of providing the pins 18' on the bracket 17' I make use of the supplemental slide 30 having the pair of pins 18' actuated toward the

pins 25' by the supplemental springs 31, the lens being thus securely clamped between the pins 18' and 25', but the pins 25' being the relatively stationary portion of the lens centering clamp. In this form of invention 70 the spring 23' may serve as a feed spring to press the lens to be slotted against the wheel, in which form I preferably pivot to the block 24' the controlling member 32 adapted to be engaged by the adjustable screw 33 75 carried by the handle 21', and in use the latch member 32 is swung upward to engage the screw 33 which is adjusted till the edge of the lens just contacts with the edge of the cutter wheel 14, after which the latch is 80 swung downward, when the spring tension will serve to shift the carriage inward toward the wheel, which will cut the lens, until the stop screw comes into engagement with the abutment block 24', limiting its inward movement and thus the slotting of the lens.

It is to be noted in connection with this form of my invention that I have illustrated two different methods of securing the 90 vertical adjustment of the lens, and likewise two means for securing its angular adjustment, which means are capable of joint or separate use. It is first to be noted that the supporting bracket is illustrated as split 95 to form the parts 17' and 17" respectively, the part 17" bearing the rod 19' and carriage, while the part 17' is rigid with the attaching block 15'. The connection between the parts 17' and 17" is such as to permit of relative vertical sliding of the parts as adjusted by the screw 34, and at the same time to permit of their relative rotation to adjust the angular position of the lens.

In addition I may, if desired, form the 105 block 17' with additional apertures 16' so arranged that the positioning pins 6 may be engaged in different pairs of apertures to control the height and also provide certain lateral apertures so that the entire device 110 may be swung around in the jaws, as should be readily apparent by reference to Figure III.

In any event it will be noted that I have provided an improved device capable either 115 of permanent attachment to a suitable base adjacent a rotating arbor to carry the wheel or capable of temporary application to existing forms of lens drills, or other devices having a rotating spindle and which in 120 either event will serve to satisfactorily hold or secure a lens and assist in the desired correct slotting of the lens.

I claim:

A lens holder for use in slotting lenses, 125 including a base block provided with means for attaching the same, a bracket rising from the block and carrying a guide bar, a stop rigidly secured on the bar, a lens holding member, a guide lug carried by said holding 130

member for sliding movement on the bar, pins carried by the holding member for engaging the lens, an actuating spring on the bar intermediate the stop and the holder, a guide lug for inwardly actuating the holder, and means for predetermining the limit of the inward movement of the holder.

In testimony whereof I affix my signature in the presence of two witnesses.

ARTHUR A. ARNOLD.
